Patented Jan. 31, 1922.

UNITED STATES PATENT OFFICE.

JOHN J. REXROTH, DECEASED, LATE OF CHICAGO, ILLINOIS, BY FANNIE W. REXROTH,
ADMINISTRATRIX.

DOOR HANGER.

1,405,374.

Specification of Letters Patent.

Patented Jan. 31, 1922.

Application filed April 15, 1921. Serial No. 461,656.

To all whom it may concern:

Be it known that JOHN J. REXROTH, late a citizen of the United States, residing at Chicago, county of Cook, and State of Illinois, has invented a new and useful Improvement 5 in Door Hangers, of which the following is a specification.

This invention relates to door hangers.

An object of the invention is to provide a 10 door hanger avoiding the necessity of installing a track different from a flat horizontal track, and to provide means in connection with the hanger for distributing the load of the door over a plurality of anti-friction rollers connected with the door.

Another object of the invention is to provide a door hanger in which the necessity of providing a guide roller for engaging the track is avoided.

20 It is also an object of the present invention to provide anti-friction rollers travelling in inclined planes while in contact with the track, so as to avoid a binding effect upon the door.

25 With these and other objects in view, an embodiment of the invention is illustrated in the accompanying drawing, to which reference is made in the following specification, the novel features being pointed out more clearly in the appended claims.

In the drawings:

Fig. 1 is a perspective view of the upper portion of a door suspended from an elevated track;

35 Fig. 2 is an enlarged sectional view through one of the hangers;

Fig. 3 is a transverse sectional view taken on line 3—3 of Fig. 2, and

40 Fig. 4 is a similar sectional view taken on line 4—4 of Fig. 2.

The door opening 1 is confined by the two uprights or door jambs 2, the upper ends of which are connected by the track supporting beam 3. The upper surface of this beam 45 supports a track preferably formed of a casting or rolled metal bar of substantially Z-profile. This track element comprises a horizontal flange 4 spaced by a vertical web 5 from the flanges 6 and 7, which are secured in some suitable way to the top and rear surface of the beam 3.

The door 8 is equipped near its top with straps 10 which are fastened to the door and which are bent rearwardly at 13, and then 55 downwardly at 11, the last named portion

being preferably spaced from the web 5 of the track element. The front part of the strap may be reinforced by a suitable corrugation, as indicated at 12.

The carriage 9 is located between the strap 60 and the back plate 11, and includes two similar castings each consisting of a wall 13, an upper track 14, extending circumferentially of the wall, and a lower track 15, both of these track portions of each casting 65 projecting inwardly towards the other casting. The spaces between the projections 14 and 15, and the projection 15 and the upper surface of the track 4 serves as a race for the anti-friction rollers 17. From Figs. 3 70 and 4 it will be noted that the path of these anti-friction rollers is approximately elliptical as it is confined by the circumferential projection 14 and turns about the ends of the projection 15. The spaces for these rollers 75 are slightly larger than the diameter of the rollers, and the rollers in the lower track will place themselves at an angle to the upper surface of the track portion 4, as indicated in Fig. 2, because the inner faces of 80 the casting 13 are undercut in their lower parts. The two sets of rollers are held at a distance from each other by spacer castings 20 which are supported on the projection 15 and which are provided with recesses 21 to 85 receive journal pins 22 projecting from the rollers. The castings 13 are secured between the strap portions by bolts 23, extending through ears 24 outside the path of the rollers. 90

Owing to the inclined position of the rollers while in engagement with the track 4, the contact area between track and rollers is greatly reduced and the possibility of binding the hanger thereby is excluded. It 95 also assures an even wear on the surface of the rollers. The entire track may be covered by a guard plate 25 which is fastened in a suitable way above the door.

Claims:

1. A door hanger, comprising in combination a strap secured to the door and projecting above the same, castings secured to the strap, said castings facing each other, rollers supported by said castings, a flat track 105 surface on which some of the rollers run, and means secured between the castings for separating the rollers into two sets and permitting angular positioning of the rollers engaging said track surface. 110

2. In a door hanger, the combination of a strap having a front portion fastened to the front face of the door and having a rear portion spaced from the front face, castings facing each other and interposed between said front and rear portion, spacing members inserted between the two castings, a metal bar presenting a flat surface upwardly above the door, and a plurality of sets of rollers, said castings being provided with channels which by the flat surface of the bar are complemented to elliptical channels, the rollers travelling in said elliptical channels.
- 10 3. In combination with a door hanger having a strap fastened to the door, a track element presenting a flat surface upwardly,

a carriage secured to the strap, and rollers rotatably mounted in said carriage, the carriage being provided with inclined wall portions adapted to place the rollers which are 20 in engagement with the track in angular position with respect to the track.

In testimony whereof, I affix my signature in the presence of two witnesses at 36 W. Randolph St., Chicago, Illinois.

Mrs. FANNIE W. REXROTH,
Administratrix of John J. Rexroth, deceased.

Witnesses:

HENRY R. WAHL,
DANIEL A. BRENNAN.
